UNITED STATES PATENT OFFICE.

WILLIAM H. POWELL, OF PHILADELPHIA, PENNSYLVANIA, ASSIGNOR TO
J. ELLIOTT SHAW, OF SAME PLACE.

DESIGN FOR A FRAME FOR ELECTRIC BELLS.

SPECIFICATION forming part of Design No. 19,118, dated May 28, 1889.

Application filed April 16, 1889. Serial No. 307,504. Term of patent 7 years.

To all whom it may concern:

Be it known that I, WILLIAM H. POWELL, a citizen of the United States, residing at Philadelphia, in the county of Philadelphia and State of Pennsylvania, have invented and produced a new and original Design for a Frame for an Electric Bell, of which the following is a specification, reference being had to the accompanying drawings, forming a part hereof, 55

wherein—

Figure 1 is a plan view showing my design. Fig. 2 is a side elevation, and Fig. 3 is an end view, of the same, these three views being deemed necessary to fully illustrate my design. 60

My invention consists in the frame for electric vibrating or stroke bells having a flat portion or main body with a number of lateral and longitudinal extensions of various lengths extending therefrom and in a plane therewith, the same having wings extending from their edges into positions at right angles with the plane of their surfaces, the edges of said frame being of ornamental outline, and said main body or outline having an ornamental center. 65

In the drawings, A represents the body of the frame, having in its center the ornamental opening A', having the appearance of a large circle with a number of smaller circles breaking through the periphery of the larger one, the center being removed and leaving the segments a of the large circle joining the smaller circle-segments, a', and forming the sharp corners a², the centers of the circles a' being in line with said corners, so that the outer edges of the smaller circles are beyond the peripheral line of the larger one. Body A has an elongated lateral leg, B, slightly tapered to its round end b, having centrally located therein the circular openings b' b², and having the straight edges b³ b⁴, on which edges, and curving upwardly therefrom, are the small L-shaped wings b⁵ b⁶, near its inner end and at right angles with the plane of the surface of said leg, the sides of said wings being square and the projecting ends pointing toward the body A, which body also has a short lateral arm, C, with the curve c between the same and the leg B, which arm has a round end, c', with a circular opening, c², cen-

trally located therein, also a straight edge, c³, and an oblique edge, c⁴, joining the broad curve c⁵ in the edge of the body A, which body also has the outwardly and laterally curved arm D, whose inner end, where it joins said body, is opposite the inner end of the leg B. The outer end of this arm is straight or squared off at d for a portion of its width, said portion forming a corner where it joins the curve c⁵. 70 The other portion of the end of the arm D projects slightly beyond the portion d and curves upwardly from the surface of said arm and at right angles therewith, forming the enlarged L-shaped wing d', having the corners of its projecting portion rounded at d² d², and a broad notch, d³, in its perpendicular edge opposite to its projecting portion. As will be observed, all of the edges of the wing d', as are all of the edges of the wings b⁵ b⁶, are at right angles with each other. The wing d' also has the circular opening d⁴ therein near the outer edge of the projecting portion of the wing a' and equidistant from its upper and lower edges. The arm D has a similar opening, d⁵, therein near its outer end and equidistant from the corner of the square portion d and the rounded edge d⁶ of said arm, which edge terminates in the straight portion d⁸, forming an angle with the surface of the wing d'. The round portion d⁶ joins the curved or concave portion d⁷, the two forming a wave-like or ogee edge for the arm D. The concavity d⁷ at its other end joins the straight edge e of the arm or broad offset E, 75 forming a corner or angle with its surface. The other edge, e', of said arm also forms a corner or angle with the surface thereof, which edge joins the curved portion e² between said edge and the leg B. 80

The arm E has a wing, e³, of the same width as said arm, having its three sides, e⁴ e⁵ e⁶, straight and at right angles with each other, the corners e⁷ thereof being round, said wing curving upwardly from the edge of the arm E into a position at right angles with the surface thereof. Said wing has therein two circular openings, e⁸, equidistant from the top and side edges of the wing e³, and both of the same size. 85

As will be observed, all of the wings of the frame extend in the same direction, and all 90

the arms or extensions are in the same plane with the body of the frame.

Having thus described my design in all its details, what I claim is—

5 The design for a frame for electric bells herein shown and described, comprising body A, having the ornamental center A', composed of the four segments a of a large circle joining the same number of segments a' of smaller circles forming the corners a², the centers of said smaller segments being between said corners, said body having the leg B, with the round end b and the straight edges b³ b⁴, having thereon and at right angles with the plane 10 of the surface of said leg the upwardly-turned L-shaped wings b⁵ b⁶, said leg also having near its ends the central circular openings, b' b², the edge b³ joining the curve c of the edge c³ of the lateral arm C with the round 15 end c' and the central circular opening, c², said arm also having the oblique edge c⁴, joining the broad curve c⁵ of the body A, said curve forming a corner with and joining the square end d of the curved arm D, said arm 20

having the enlarged upwardly-turned L-shaped wing, d', having the round corners d², the notch d³, and the circular opening d⁴ midway between its rounded corners, said arm also having the central circular opening, d⁵, near its outer end, and the straight edge d⁶, joining the round edge d⁶, the latter joining the curve d⁷, which joins the straight edge e of the broad arm E, said arm also having the straight edge e', joining the curve e² of the leg B and the upturned wing e³ of the 30 same width as said arm, said wing having square edges e⁴ e⁵ e⁶, and the circular openings e⁷ e⁸, equidistant each from the rounded corners e⁷ e⁸ of said wing, as set forth.

In testimony that I claim the foregoing I have hereunto set my hand, at the city of Philadelphia, Pennsylvania, this 12th day of April, A. D. 1889.

WILLIAM H. POWELL.
